UNITED STATES PATENT OFFICE.

ARTHUR H. ADAMS, JR., OF PRINCETON, NEW JERSEY.

DESIGN FOR A PAPER KNIFE.

Application filed April 12, 1928. Serial No. 26,296. Term of patent 14 years.

To all whom it may concern:

Be it known that I, ARTHUR H. ADAMS, Jr., a citizen of the United States, residing at Princeton, in the county of Mercer and State of New Jersey, have invented a new, original, and ornamental Design for Paper Knives, of which the following is the specification, reference being had to the accompanying drawings forming part thereof.

Fig. 1 is a plan view of a paper knife showing my new design.

Fig. 2 is an edge elevation of the same.

I claim:

The ornamental design for a paper knife as shown.
